INSOLE

Claude H. Daniels, Greenwich, Conn.

Application November 4, 1940, Serial No. 364,228

7 Claims.

(Cl. 36—22)

This invention relates to improvements in insoles for boots and shoes, to methods of reinforcing insoles and to the improved material used for the reinforcement of insoles.

In shoe manufacture there are opposing factors. First, the shoe must be made durable and strong to retain its shape and prevent breaking down and to securely hold the stitches, but the shoe must not be too stiff. It is desired that the shoe shall be relatively flexible, particularly at the ball area so that the shoe will bend to accommodate the normal movement of the foot in walking. In the welt construction, for example, it is customary to reinforce the bottom of the insole within the area surrounded by the upstanding rib, by cementing a piece of canvas or gem duck thereto. The canvas tends to hold the stitches which pass through the rib more securely and prevents spreading of the insole. The canvas stiffens the shoe which is undesirable. Recently it has been proposed to use in place of the canvas or gem duck a tape which is cemented to the upstanding rib and to the bottom face of the sole around the margin of the upstanding rib, but the tape does not extend across the shoe. In other types of shoes it has been suggested that the insole be cut to a thin layer which is reinforced by a sheet of fabric. In these prior constructions the fabric, canvas, gem duck or otherwise, has been relatively non-stretchable.

It is an object of my invention to use in shoe manufacture a special material which has considerable stretch in one direction but is relatively non-stretchable in a transverse direction, and to apply this fabric to insoles in such a manner that the fabric will stretch longitudinally of the shoe and permit the flexing of the shoe in the normal manner thereby serving to reinforce the shoe but at the same time retaining the flexibility.

It is a further object of my invention to employ a textile fabric which has been knitted, woven or otherwise fabricated in such a manner that it is stretchable in one direction and is relatively non-stretchable in a transverse direction.

It is a particular object of my invention to employ in the manufacture of welt shoes my special fabric in place of the usual gem duck which is applied to the bottom of the insole in the usual manner, or to employ a strip which is longitudinally stretchable, cemented to the rib and to the adjacent portion of the insole.

It is a further object of my invention to provide an improved insole which for example may be used in the manufacture of compo, stitch-down, pre-welt or McKay shoes or the like comprising a relatively thin flexible insole reinforced with my special fabric which is yieldable longitudinally of the sole but is relatively non-yieldable or non-stretchable transversely of the sole.

Further objects and advantages of my improvements will be more readily apparent from the following description of preferred embodiments thereof taken in connection with the attached drawings in which:

Fig. 1 is a bottom view of an insole for a welt shoe;

Fig. 2 is a bottom view of a relatively thin flexible insole having a fabric reinforcement applied thereto;

Fig. 3 is a bottom view of an insole for a welt shoe having a reinforcing tape applied to the outside of the rib;

Fig. 4 is a fragmentary bottom view of the forepart of an insole, a portion of which has been reduced in thickness and reinforced by a fabric;

Fig. 5 is a cross-section taken on the plane indicated 5—5 in Fig. 3;

Fig. 6 is a cross-section similar to Fig. 5 but showing a modification;

Fig. 7 is a section taken on the plane indicated 7—7 in Fig. 4;

Fig. 8 is a bottom view of an insole for a welt shoe, the ball portion of which has been weakened by slashing and having a fabric reinforcement applied thereto;

Fig. 9 is a side elevation of the insole shown in Fig. 8;

Fig. 10 is a cross-section taken on the plane indicated 10—10 in Fig. 8;

Fig. 11 is a longitudinal section taken on the plane indicated 11—11 in Fig. 8; and

Fig. 12 is a longitudinal section of a slashed insole having a fabric reinforcement; and

Fig. 13 is an enlarged detail view of one form of knit which may be used for the fabric used to reinforce the insoles.

I have found many advantages in the use of specially fabricated material for the reinforcement of insoles which is made in such a manner that the material has more than the normal stretch in one direction but is relatively non-stretchable in a transverse direction. One method is to knit the fabric in a special manner as shown by the knitted material 10 in Fig. 13. In this case the fabric as it is knit is weighted

or stretched to take out most all the stretch in an up-and-down direction as shown in Fig. 13, while the stretchability of the fabric transversely is increased. The material may be made in other ways, such as by weaving or otherwise. Woven fabric which has heretofore been used to reinforce insoles may have had a small amount of stretch in one direction, but has not been applied to the insoles in any special manner so that the stretch is in a particular direction, namely lengthwise of the insole, and even if so applied the old woven material would be of little help in permitting flexing of the insole due to the slight amount of stretch present in the woven material. If my reinforcing material is made by weaving it would be made to have more than the normal stretch so that when properly applied to the insole it will not tend to stiffen the insole and resist flexing. Instead the material would be readily stretchable lengthwise of the sole so as to allow full flexing of the insole and will be relatively non-stretchable transversely of the insole and thereby prevent spreading.

My knitted, woven or otherwise fabricated material may, if desired, be treated with a rubber solution such as latex, either by coating one or both surfaces or by impregnation, the rubber serving to impart elasticity to the fabric and prevent raveling or fraying of the edges when the material is cut into pieces to be applied to insoles. A thin sheet of rubber could also be cemented to the fabric. The material can also be made or cut in the form of a strip which is stretchable lengthwise thereof.

I have disclosed in Fig. 1 an insole 12 for a welt shoe which is of ordinary construction having a rib 14. It is customary practice when thin insoles are used for the purpose of flexibility to reinforce the insole by a method known as "gemming" which consists in applying a fabric known as gem duck to the pocket formed within the rib 14. In my method the reinforcing fabric 16 which is cemented to the bottom face of the insole and to the inner side of the rib is made as previously described in a special manner to be stretchable lengthwise of the insole and to be relatively non-stretchable transversely of the insole. The reinforcement 16 serves to strengthen the rib 14 to more securely hold the stitches and tends to prevent spreading while at the same time preserving and retaining the normal flexibility of the insole.

Instead of using a full piece of fabric reinforcement as shown in Fig. 1, I may use a reinforcement in the form of a strip as shown in Figs. 3 and 5 in which the usual welt insole 18 has a rib 20 and the reinforcing tape 22 is cemented to the insole and to the outer face of the rib. The strip serves to reinforce the rib as well as the margin of the insole. The reinforcement of the rib will hold the stitches more securely. Reinforcement of the marginal edge of the insole makes a firm edge on the insole which does not curl and the shoe will better retain its shape. The strip 22 is made to be stretchable lengthwise of the strip and therefore does not tend to stiffen the sole or prevent the normal flexing. It should be further understood that if desired a strip reinforcement 23 may be cemented to the inner side of the upstanding rib or lip 20 and to the insole adjacent the rib as shown in Fig. 6.

The fabric reinforcement may be applied to the insoles used in other types of shoe constructions such as compo, stitchdown, pre-welt, McKay or the like. Fig. 2 shows an insole 24 which has

been made relatively thin throughout its length so as to increase the flexibility of the shoe in which it is to be used. I have shown a fabric reinforcement 26 applied to the thin sole 24 at least over the forepart thereof and extending approximately to the marginal edge of the insole. The fabric may be cemented to the insole in any desired manner. The fabric is applied in such a manner that the stretch is lengthwise of the insole. The fabric reinforcement serves to stabilize the insole but does not materially stiffen the insole.

An alternative method is shown in Figs. 4 and 7 in which the sole 28 is reduced in thickness at the ball portion 30 such as by skiving or grinding away some of the material. The insole is reinforced by cementing a fabric reinforcement 32 into the space formed by the removal of a portion of the insole. The fabric 32 is applied in such a manner that it is stretchable lengthwise of the insole.

In Figs. 8 to 11 inclusive I have shown a welt insole 34 having the upstanding rib 36, the insole being rendered more flexible across the ball portion by the slashes or cuts 38 which extend through the rib 36 as indicated at 40 in Fig. 9. I have applied to the insole a fabric reinforcement 42 by cementing in the same manner as shown in Fig. 1. The fabric serves to reinforce the entire insole and particularly the weakened area tending to keep the slashes closed up by permitting flexing of the insole due to the fact that the fabric 42 is stretchable lengthwise of the insole.

Fig. 12 discloses a plain insole 44 having slashes 46 and reinforced by the fabric 48 which is cemented to the insole to be stretchable lengthwise of the insole.

I claim:

1. An insole having a slashed area at the forepart and a reinforcement adhesively applied to the under side of the insole and extending over the slashed area comprising knit fabric material stretchable longitudinally of the sole and relatively non-stretchable transversely of the sole.

2. An insole for a welt shoe having an upstanding rib and a reinforcement adhesively secured to the bottom face of the insole at the ball portion thereof and adhesively secured to the inner side of the upstanding rib, said reinforcement comprising knit fabric material stretchable longitudinally of the sole and relatively non-stretchable transversely of the sole.

3. An insole for a shoe having a weakened area at the under side of the forepart thereof and a reinforcement adhesively applied to the under side of the sole and extending over the weakened area, comprising knit fabric material stretchable longitudinally of the sole and relatively non-stretchable transversely of the sole.

4. An insole for a welt shoe having a weakened area at the under side of the forepart thereof and a reinforcement adhesively applied to the under side of the sole and extending over at least a portion of the weakened area, comprising knit fabric material stretchable longitudinally of the sole and relatively non-stretchable transversely of the sole.

5. In a welt insole having an upstanding lip, a reinforcement in the form of a strip of knit fabric material cemented to one side of the lip and to the adjacent portion of the insole, said strip of knit fabric material being stretchable

longitudinally of the lip and relatively non-stretchable transversely of the lip.

6. In a welt insole having an upstanding lip, a reinforcement in the form of a strip of knit fabric material cemented to the outside of the lip and to the marginal edge of the insole, said strip of knit fabric material being stretchable longitudinally of the lip and relatively non-stretchable transversely of the lip whereby said strip serves as a reinforcement of the lip and the 10

marginal edge of the insole while retaining the flexibility of the insole.

7. In a welt insole having an upstanding lip, a reinforcement in the form of a strip of knit fabric material cemented to the inside of the lip and to the bottom face of the insole adjacent the lip, said strip of knit fabric material being stretchable longitudinally of the lip and relatively non-stretchable transversely of the lip.
